UNITED STATES PATENT OFFICE.

SUSAN COOPER WOLFSKILL, OF WINTERS, CALIFORNIA.

BABY-BUGGY.

SPECIFICATION forming part of Letters Patent No. 733,889, dated July 14, 1903.

Application filed March 16, 1903. Serial No. 148,098. (No model.)

To all whom it may concern:

Be it known that I, SUSAN COOPER WOLFSKILL, a citizen of the United States, residing at Winters, in the county of Yolo and State 5 of California, have invented a new and useful Baby-Buggy, of which the following is a specification.

This invention relates to certain improvements in children's carriages, and has for its 10 principal object to provide an improved form of carriage which may be folded together in such manner as to occupy but small space when not in use or may be extended for use as a carriage or employed as a crib, if desired.

15 With these and other objects in view the invention consists in the novel construction and arrangement of parts hereinafter described, illustrated in the accompanying drawings, and particularly pointed out in the 20 appended claims, it being understood that various changes in the form, proportions, size, and minor details of the structure may be made without departing from the spirit or sacrificing any of the advantages of the invention.

25 In the accompanying drawings, Figure 1 is a longitudinal sectional elevation of a baby-buggy constructed in accordance with the invention. Fig. 2 is a transverse sectional elevation of the same on the line 22 of Fig. 1. Fig. 3 is a detail perspective view of the buggy-body detached. Fig. 4 is a detached perspective view of one of the connections of the front supporting-springs.

30 Similar numerals of reference are employed to indicate corresponding parts throughout the several figures of the drawings.

The front and rear wheels 5 and 6 are of the ordinary construction and connected by 40 axles 7 and 8, respectively, to the handles or shafts 9 of the carriage.

45 The body portion of the buggy is located wholly above the tops of the wheels in order to permit lateral extension of the body to form a carriage of extra width or to add to the comfort of the occupant when the device is used as a crib. The fixed portion of the bottom of the buggy is preferably in the form of a board or plate of sheet metal 10, to the 50 under side of which are connected the upper ends of a pair of springs 11, the springs being

formed of strips of steel bent into U shape, the upper arms of said strips being rigidly secured to the bottom board and the lower ends being supported by the lower portions 55 of the handles or shafts 9 of the carriage. In order to permit longitudinal adjustment of the spring with respect to the handles 9, the handles are provided with elongated clips or sleeves 12, forming guides for the lower arms 60 of the springs, excessive movement being prevented by depending arms 13, carried by the springs and adapted to engage against the rear ends of the clips or sleeves 12.

The front portion of the carriage is formed 65 of three main members, including the bottom board 10 and laterally-adjustable side members 14 and 15, the bottom portions of which are in the form of thin boards or sheets of metal and each provided with transversely-disposed slots 16, through which extend headed bolts or pins 17, the bolts or pins passing also through suitable openings in the bottom board 10. The members 14 and 15 are secured to or formed integral with side boards 70 or walls formed of woven cane, fabric, or other suitable material, and to the members 14 and 15 are secured foot board-sections 19 and 20, respectively. The foot board-section 19 is provided with a headed bolt or pin 21, adapted 75 to a transversely-extending slot 22, formed in the member 20, and said member 20 is further provided with oppositely-facing spring-catches 23 and 24, arranged adjacent to the opposite ends of the slot 22 and adapted to 80 automatically engage with the bolt at opposite ends of the slot and lock the sections in either open or closed positions. The several members which constitute the front portion of the carriage are overlapped in such 85 manner as to permit of extensive lateral adjustment of the side members with the several bolts and slots as guides, the buggy being widened out in order to afford sufficient room for the child and to permit the device 90 to be used as a crib.

The rear portion of the buggy-body is substantially the same in construction as the front portion and comprises a bottom board 95 30 and laterally-adjustable side members 31 and 32, the side members being provided with slots 33 and the bottom board with suitable

openings for the passage of headed bolts 34 for guiding and holding the several members in position. The side members may be provided with a headboard formed of overlapping sections and arranged in the same manner as the footboard or may be in the form illustrated in Fig. 2 and spaced from each other when the parts are opened out, a suitable locking-bar 38 being employed to connect the sections to each other and serving also as a support for a removable back-piece or cushion member of the character usually employed in buggies of this class.

The bottom board 30 is provided with springs 39, rigidly secured at one end to the board and at the opposite end to the rear wheel-axle 8 or to a portion of the handles or shaft, these springs being constructed and arranged in the usual manner.

20 The side members constituting the front portion of the body overlap those members which form the rear portion, and in the side members of the rear section are horizontally-disposed slots 42, adapted for the reception 25 of headed pins 43, carried by the side members of the front portion, there being suitable spring-catches disposed at or near each end of the slots adapted to automatically engage and lock the headed pins and hold the 30 carriage in its adjusted position. The longitudinal adjustment of the members is rendered possible by the construction of the springs 11 and the spring guiding-clips 12, the whole of the front section being moved 35 forward to any desired extent.

The wheels of the carriage may be placed closely together and the several members of the body so constructed as to permit of the contraction of the body within small 40 compass to permit ready transportation from place to place, as well as to enable the device to be stored away when not in use.

The buggy is preferably made so as to accommodate a child of ordinary size; but when 45 necessary it may be readily lengthened out in order to hold two children, or it may be extended laterally to form a crib for one or two children.

As the bottom of the body portion is wholly 50 above the supporting-wheels, extensive lateral and longitudinal adjustment is permitted to accommodate a child of any age or to permit its use as a crib.

Having thus described my invention, what 55 I claim is—

1. In a baby-buggy, a body formed of a plurality of overlapping sections adjustable both laterally and longitudinally.
2. In a baby-buggy, a body formed of a 60 plurality of overlapping sections adjustable

both laterally and longitudinally, and catches for locking the sections in adjusted position.

3. In a baby-buggy, a body comprising head and foot members adjustable longitudinally with respect to each other, each of 65 such members comprising a plurality of overlapping and laterally-adjustable sections.

4. In a baby-buggy, a body comprising head and foot members adjustable longitudinally with respect to each other, pin-and- 70 slot connections for maintaining the parts in proper relative position, and each of such members being formed of a plurality of overlapping laterally-adjustable sections having pin-and-slot connections, and catches for 75 locking the several parts in adjusted position.

5. In a baby-buggy, the combination with the wheels and axles, of a body comprising head and foot members adjustable longitudinally with respect to each other, springs 80 having a fixed connection with one member and with the running-gear, and a second set of springs connected to the opposite member and having an adjustable connection with the running-gear.

6. The combination in a baby-buggy, of the running-gear including longitudinally-extending handle members or side-bars connecting the front and rear axles, clips or sleeves carried by the handle members, a 90 body portion comprising longitudinally-adjustable members, springs connecting the rear members to the rear axle, and springs secured to the foot member and guided by said clips or sleeves.

7. The combination in a baby-buggy, of the running-gear including longitudinally-disposed handle-bar members or side-bars connecting the front and rear axles, head and foot members adjustable longitudinally and each provided with supporting-springs, clips or sleeves carried by the handle members and embracing the front springs to permit longitudinal adjustment thereof, laterally-extending arms carried by said springs to prevent excessive movement, laterally-adjustable side members carried by both the head and foot members and each provided with transversely-disposed guiding-slots, headed bolts extending through said slots, and 100 springs for locking the several members in adjusted positions.

In testimony that I claim the foregoing as my own I have hereto affixed my signature in the presence of two witnesses.

SUSAN COOPER WOLFSKILL.
